US012533565B2

(12) **United States Patent**
Nielsen et al.

(10) **Patent No.:** **US 12,533,565 B2**
(45) **Date of Patent:** **Jan. 27, 2026**

(54) **DEVICES, SYSTEMS, AND METHODS FOR EXERCISE DEVICE CONTROL**

(71) Applicant: **iFIT Inc.**, Logan, UT (US)

(72) Inventors: **Rebecca Lynn Nielsen**, Logan, UT (US); **Jessie Dent**, Logan, UT (US)

(*) Notice: Subject to any disclaimer, the term of this patent is extended or adjusted under 35 U.S.C. 154(b) by 91 days.

(21) Appl. No.: **18/660,217**

(22) Filed: **May 9, 2024**

(65) **Prior Publication Data**

(57) **ABSTRACT**

A volume control system may receive and play a program audio stream at the exercise device, the program audio stream played with a program volume, wherein the program audio stream is part of an exercise program package, the exercise program package including exercise device controls that adjust an operating parameter of the exercise device, the program audio stream synchronized with the exercise device controls. A volume control system may receive and play a media audio stream at the exercise device, the media audio stream played with a media volume. A volume control system may be based on a content of the exercise program package, adjusting a relative volume of the program audio stream to emphasize the program audio stream.

DEVICES, SYSTEMS, AND METHODS FOR EXERCISE DEVICE CONTROL

BACKGROUND

Health is a critical part of a person's well-being. People cultivate their health through health actions, including exercise, diet, lifestyle, and so forth. People may use exercise systems to facilitate their health journey. Indoor exercise has increased in popularity and accessibility. Many people exercise indoors with the aid of an exercise device. Exercise devices may be designed to simulate outdoor exercise activities, such as a treadmill to simulate running, a stationary bicycle to simulate cycling, or a rower to simulate rowing. Additionally, or alternatively, exercise devices may be designed to exercise a certain muscle or muscle group, reduce the impact or force applied to the user, aid in certain types of indoor exercises, perform any other function, and combinations thereof.

BRIEF SUMMARY

In some aspects, the techniques described herein relate to a method implemented on an exercise device. A volume control system receives and plays a program audio stream at the exercise device. The program audio stream is played with a program volume. The program audio stream is part of an exercise program package. The exercise program package includes exercise device controls that adjust an operating parameter of the exercise device. The program audio stream is synchronized with the exercise device controls. The volume control system receives and plays a media audio stream at the exercise device. The media audio stream is played with a media volume. Based on a content of the exercise program package, the volume control system adjusts a relative volume of the program audio stream to emphasize the program audio stream.

In some aspects, the techniques described herein relate to a method implemented on an exercise device. The exercise device implements an exercise program package. The exercise program package includes exercise device controls that adjust an operating parameter of the exercise device. The exercise program package further includes a program video stream and a program audio stream. The program video stream and the program audio stream are synchronized with the exercise device controls. The program audio stream is played through speakers on the exercise device. The exercise device presents third-party media on the exercise device. The exercise device displays, on a display of the exercise device, a media video stream of the third-party media and a media audio stream through the speakers. When the exercise program package reaches a priority content, the volume control system alters a relative volume of the media audio stream.

In some aspects, the techniques described herein relate to a method for operating an exercise device. The exercise device implements an exercise program package on the exercise device. The exercise program package includes a video portion and a program media stream. The video portion is displayed on a display of the exercise device and the program media stream is played on a speaker of the exercise device. While displaying the video portion on the display and playing the program media stream on the speaker of the exercise device, the exercise device receives a selection of a selectable icon overlaid over the video portion on the display. Based on the selection, and while implementing the exercise program package, the exercise

device replaces the video portion on the display with a media video portion of a third party media and playing a media video stream simultaneously with the program media stream.

5 This summary is provided to introduce a selection of concepts that are further described below in the detailed description. This summary is not intended to identify key or essential features of the claimed subject matter, nor is it intended to be used as an aid in limiting the scope of the 10 claimed subject matter.

Additional features and advantages of embodiments of the disclosure will be set forth in the description which follows, and in part will be obvious from the description, or may be learned by the practice of such embodiments. The features 15 and advantages of such embodiments may be realized and obtained by means of the instruments and combinations particularly pointed out in the appended claims. These and other features will become more fully apparent from the 20 following description and appended claims, or may be learned by the practice of such embodiments as set forth hereinafter.

BRIEF DESCRIPTION OF DRAWINGS

25 In order to describe the manner in which the above-recited and other features of the disclosure can be obtained, a more particular description will be rendered by reference to specific implementations thereof which are illustrated in the 30 appended drawings. For better understanding, the like elements have been designated by like reference numbers throughout the various accompanying figures. While some of the drawings may be schematic or exaggerated representations of concepts, at least some of the drawings may be 35 drawn to scale. Understanding that the drawings depict some example implementations, the implementations will be described and explained with additional specificity and detail through the use of the accompanying drawings in which:

40 FIG. 1 is a representation of a graphical user interface (GUI) that may be presented on a display of an exercise device, according to at least one embodiment of the present disclosure.

45 FIG. 2 is a representation of a GUI that may be presented on a display of an exercise device, according to at least one embodiment of the present disclosure.

FIG. 3 is a representation of a GUI that may be presented on a display of an exercise device, according to at least one embodiment of the present disclosure.

50 FIG. 4 is a representation of a GUI that may be presented on a display of an exercise device, according to at least one embodiment of the present disclosure.

FIG. 5 is a representation of a GUI that may be presented on a display of an exercise device, according to at least one embodiment of the present disclosure.

FIG. 6 is a representation of a GUI that may be presented on a display of an exercise device, according to at least one embodiment of the present disclosure.

FIG. 7 is a representation of a GUI that may be presented on a display of an exercise device, according to at least one embodiment of the present disclosure.

FIG. 8 is a representation of a GUI that may be presented on a display of an exercise device, according to at least one embodiment of the present disclosure.

65 FIG. 9 is a representation of a GUI that may be presented on a display of an exercise device, according to at least one embodiment of the present disclosure.

FIG. 10 is a representation of a GUI that may be presented on a display of an exercise device, according to at least one embodiment of the present disclosure.

FIG. 11 is a representation of a GUI that may be presented on a display of an exercise device, according to at least one embodiment of the present disclosure.

FIG. 12 is a representation of a GUI that may be presented on a display of an exercise device, according to at least one embodiment of the present disclosure.

FIG. 13 is a representation of a GUI that may be presented on a display of an exercise device, according to at least one embodiment of the present disclosure.

FIG. 14 is a representation of a GUI that may be presented on a display of an exercise device, according to at least one embodiment of the present disclosure.

FIG. 15 is a representation of a GUI that may be presented on a display of an exercise device, according to at least one embodiment of the present disclosure.

FIG. 16 is a representation of a GUI that may be presented on a display of an exercise device, according to at least one embodiment of the present disclosure.

FIG. 17 is a representation of a GUI that may be presented on a display of an exercise device, according to at least one embodiment of the present disclosure.

FIG. 18 is a representation of a GUI that may be presented on a display of an exercise device, according to at least one embodiment of the present disclosure.

FIG. 19 is a representation of a GUI that may be presented on a display of an exercise device, according to at least one embodiment of the present disclosure.

FIG. 20 is a representation of a GUI that may be presented on a display of an exercise device, according to at least one embodiment of the present disclosure.

FIG. 21 is a representation of a GUI that may be presented on a display of an exercise device, according to at least one embodiment of the present disclosure.

FIG. 22 is a representation of a GUI that may be presented on a display of an exercise device, according to at least one embodiment of the present disclosure.

FIG. 23 is a representation of a GUI that may be presented on a display of an exercise device, according to at least one embodiment of the present disclosure.

FIG. 24 is a representation of a GUI that may be presented on a display of an exercise device, according to at least one embodiment of the present disclosure.

FIG. 25 is a representation of a GUI that may be presented on a display of an exercise device, according to at least one embodiment of the present disclosure.

FIG. 26 is a representation of a GUI that may be presented on a display of an exercise device, according to at least one embodiment of the present disclosure.

FIG. 27 is a representation of a GUI that may be presented on a display of an exercise device, according to at least one embodiment of the present disclosure.

FIG. 28 is a representation of a volume control system, according to at least one embodiment of the present disclosure.

FIG. 29 is a flowchart of a method for controlling an exercise device, according to at least one embodiment of the present disclosure.

FIG. 30 is a flowchart of a method for controlling an exercise device, according to at least one embodiment of the present disclosure.

FIG. 31 is a flowchart of a method for controlling an exercise device, according to at least one embodiment of the present disclosure.

FIG. 32 is a representation of a computing system, according to at least one embodiment of the present disclosure.

DETAILED DESCRIPTION

This disclosure generally relates to devices, systems, and methods for controlling an exercise device. A graphical user interface for an exercise device includes one or more selectable icons presented on a video display overlaid over a video (such as third-party media and/or an exercise program). Selection of the selectable icons may facilitate changing of one or more settings of the exercise device. In accordance with at least one embodiment of the present disclosure, selection of the selectable icons may change a setting of the exercise device without interrupting playing of the media on the display. In some embodiments, selection of the selectable icons may display third-party media on the display without interrupting the implementation of the exercise program. This may allow the user to seamlessly select and implement the exercise program and third-party media based on his or her desires and interests.

In accordance with at least one embodiment of the present disclosure, the user may adjust the relative volume of the audio streams of the exercise program and the third-party media. For example, while the user is performing a workout based on the exercise program that the exercise device implements, the user may increase the relative volume of the third-party media and decrease the relative volume of the exercise program. In some embodiments, the exercise device may, based on content of the exercise program, adjust the relative volume of the exercise program to emphasize or highlight the audio stream of the exercise program. This may facilitate the user hearing critical instructions, raising the user's awareness of changes to the operating parameters of the exercise device, and highlighting other portions of the exercise program. In this manner, the safety of the implementation of the exercise device may be increased.

FIG. 1 is a representation of a graphical user interface (GUI) 100 that may be presented on a display of an exercise device, according to at least one embodiment of the present disclosure. The GUI 100 may include a background image or video display. The background image or video display may be an image or video from any source, such as an image or video from an exercise program or an image or video from third-party media. The third-party media may be any third-party media, including streaming videos streamed via a streaming service, television shows, movies, user original content, home videos, any third-party media, and combinations thereof.

The GUI illustrated includes one or more menus. A lower menu 102 or banner located along a lower surface of the GUI 100 includes buttons or selectable icons that may be selected to perform functions. For example, the lower menu 55 may include workout controls 104, media controls 106, a home button 108, a back button 110, and so forth.

While implementing an exercise program, the user may select one of the selectable icons. Without interrupting the media displayed in the background of the GUI 100 and/or without interrupting the exercise program, the selection of the selectable icon may open a menu and/or change screens to allow the user to perform further actions. For example, when the user presses the workout controls 104 selectable icon, the exercise device may adjust the exercise program, such as by pausing the exercise program or adjusting one or more of the exercise device parameters. In some embodiments, when the user presses the media controls 106, a new

media application may open, allowing the user to select additional media without interrupting the exercise program. When the user presses the home button 108, the user may be taken to a screen allowing him or her to select additional media, adjust setting, adjust the exercise program, and so forth. The back button 110 may take the user to a previously viewed screen.

The GUI 100 may further include a top banner 112. The top banner 112 may overlay the background image. The top banner 112 may include information regarding the exercise activity, such as distance, time elapsed, pace, heartrate, incline, speed, and so forth. One or more of the elements of the top banner 112 may be a selectable icon. This may pull up additional menus or elements that may provide additional information about the exercise program and/or allow the operator to adjust the operating parameters of the exercise program.

FIG. 2 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, the lower menu 102 includes additional workout controls 104, such as speed and incline controls. The workout controls 104 may be selectable icons. When the user selects the selectable icons, the exercise device may change the operating parameters of the exercise device without stopping playing of the third-party media in the background of the GUI 100.

FIG. 3 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, the top banner 112 includes three icons representing exercise information, including distance traveled, time remaining, and speed. While seven icons are illustrated in FIG. 1 and FIG. 2, and three icons are illustrated in FIG. 3, it should be understood that any number of icons may be illustrated in the top banner 112.

FIG. 4 is a representation of a GUI 100 that may be presented on a display of an exercise device, according to at least one embodiment of the present disclosure. The GUI 100 may include a background image or video display, with a lower menu 102 overlaid over the video display. In the embodiment shown, a settings menu 114 may be overlaid over the video display. The settings menu 114 may be invoked or presented based on the selection of a selectable icon. The settings menu 114 may allow the user to change one or more settings of the GUI 100, such as the presentation of one or more of settings, statistics, widgets, charts, and fullscreen mode. Selection of the selectable icons in the settings menu 114 may cause the exercise device to overlay the associated menu, banner, widget, or chart over the background image. As discussed herein, selection of the selectable icons may cause the exercise device to overlay the associated element while playing the media and/or exercise program on the display (e.g., without interrupting the media and/or the exercise program).

FIG. 5 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a settings menu 114 may be overlaid over the video display. The settings

menu 114 may be invoked or presented based on the selection of a selectable icon. The settings menu 114 may allow the user to change one or more settings of the GUI 100, such as the presentation of one or more of settings, statistics, widgets, charts, and fullscreen mode. Selection of the selectable icons in the settings menu 114 may cause the exercise device to overlay the associated menu, banner, widget, or chart over the background image. As discussed herein, selection of the selectable icons may cause the exercise device to overlay the associated element while playing the media and/or exercise program on the display (e.g., without interrupting the media and/or the exercise program).

FIG. 6 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a media settings menu 116 may be overlaid over the video display and the top banner 112. The media settings menu 116 may be invoked or presented based on the selection of a selectable icon. The media settings menu 116 may allow the user to change one or more settings of the GUI 100, such as the presentation of one or more of audio controls, Bluetooth connection (or other wireless connection), exercise program features, display settings. Selection of the selectable icons in the media settings menu 116 may cause the exercise device to adjust the associated setting. As discussed herein, adjusting the settings in the media settings menu 116 may occur while playing the media and/or exercise program on the display (e.g., without interrupting the media and/or the exercise program).

FIG. 7 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a media settings menu 116 may be overlaid over the video display and the top banner 112. The media settings menu 116 may be invoked or presented based on the selection of a selectable icon. The media settings menu 116 may allow the user to change one or more settings of the GUI 100, such as the presentation of one or more of audio controls, Bluetooth connection (or other wireless connection), exercise program features, display settings. Selection of the selectable icons in the media settings menu 116 may cause the exercise device to adjust the associated setting. As discussed herein, adjusting the settings in the media settings menu 116 may occur while playing the media and/or exercise program on the display (e.g., without interrupting the media and/or the exercise program).

FIG. 8 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a media settings menu 116 may be overlaid over the video display and the top banner 112. The media settings menu 116 may be invoked or presented based on the selection of a selectable icon. The media settings menu 116 may allow the user to change one or more settings of the GUI 100, such as the presentation of one or more of audio controls, Bluetooth connection (or other wireless connection), exercise program features, display settings. Selection of the selectable icons in the media

settings menu 116 may cause the exercise device to adjust the associated setting. As discussed herein, adjusting the settings in the media settings menu 116 may occur while playing the media and/or exercise program on the display (e.g., without interrupting the media and/or the exercise program).

FIG. 9 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a media settings menu 116 may be overlaid over the video display and the top banner 112. The media settings menu 116 may be invoked or presented based on the selection of a selectable icon. The media settings menu 116 may allow the user to change one or more settings of the GUI 100, such as the presentation of one or more of audio controls, Bluetooth connection (or other wireless connection), exercise program features, display settings. Selection of the selectable icons in the media settings menu 116 may cause the exercise device to adjust the associated setting. The user may adjust settings in any manner, such as via a slider or two-position button. As discussed herein, adjusting the settings in the media settings menu 116 may occur while playing the media and/or exercise program on the display (e.g., without interrupting the media and/or the exercise program).

FIG. 10 is a representation of a GUI 100 that may be presented on a display of an exercise device, according to at least one embodiment of the present disclosure. The GUI 100 may include a background image or video display, with a lower menu 102 overlaid over the video display. In the embodiment shown, a media settings menu 116 may be overlaid over the video display. The media settings menu 116 may be invoked or presented based on the selection of a selectable icon. The media settings menu 116 may allow the user to change one or more settings of the GUI 100, such as the presentation of one or more of audio controls, Bluetooth connection (or other wireless connection), exercise program features, display settings. Selection of the selectable icons in the media settings menu 116 may cause the exercise device to adjust the associated setting. The user may adjust settings in any manner, such as via a slider or two-position button. As discussed herein, adjusting the settings in the media settings menu 116 may occur while playing the media and/or exercise program on the display (e.g., without interrupting the media and/or the exercise program).

FIG. 11 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a widget 118 is overlaid over the background display. Presentation of the widget 118 has pushed the top banner 112 to the left to allow both the widget 118 and all of the elements or icons of the top banner 112 to be shown. The widget 118 may include any type of information, including heartrate and/or heartrate zone information. The GUI 100 further includes a notification 120. The notification 120 may provide the user with information. The information may be any type of information, such as training information, heartrate information, health information, any other information, and combinations thereof.

FIG. 12 is a representation of a GUI 100 that may be presented on a display of an exercise device, according to at

least one embodiment of the present disclosure. The GUI 100 may include a background image or video display, with a lower menu 102 and a top banner 112 overlaid over the video display. In the embodiment shown, a training button 122 is overlaid over the background display. Selection of the training button 122 may facilitate the presentation of the widget 118 and/or the notification 120 illustrated in FIG. 11.

FIG. 13 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a chart 124 is overlaid over the background display above the lower menu 102. The chart 124 may include information associated with the exercise program, such as incline and/or speed. Multiple parameters may be illustrated on the chart 124.

FIG. 14 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a chart 124 is overlaid over the background display above the lower menu 102. The chart 124 may include information associated with the exercise program, such as incline and/or speed. Multiple parameters may be illustrated on the chart 124. In the embodiment shown, a settings menu 114 may be overlaid over the video display, including the chart 124. The settings menu 114 may be invoked or presented based on the selection of a selectable icon. The settings menu 114 may allow the user to change one or more settings of the GUI 100, such as the presentation of one or more of settings, statistics, widgets, charts, and fullscreen mode.

FIG. 15 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a warning 126 is overlaid over an entirety of the display, including overlaid over the top banner 112 and the lower menu 102. The warning 126 includes icons describing the warning, including a pause icon 128 and a key icon 130. In the embodiment shown, the warning 126 indicates that the safety key is removed from the exercise device. During presentation of the warning, the exercise program and/or the third-party media may be stopped.

FIG. 16 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a warning 126 is overlaid over an entirety of the display, including overlaid over the top banner 112 and the lower menu 102. The warning 126 includes icons describing the warning, including a pause icon 128. In the embodiment shown, the safety key has been returned, and the user may resume the exercise program by pressing the pause icon 128.

FIG. 17 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a volume icon 132 is presented on a left side of the display. The volume icon

132 may be representative of any volume. For example, the volume icon 132 may be representative of the total display volume, the volume of the exercise program, the volume of the third-party media, the volume of music, any other volume, and combinations thereof. In some embodiments, the volume may be a representation of a relative volume between the exercise program and third party media.

FIG. 18 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, manual controls for the exercise device are presented overlaid over the background video. The manual controls may include incline controls 134 and speed controls 136. The incline controls 134 and the speed controls 136 may be sliders to present additional information or selectable options for the user. Presenting the incline controls 134 and the speed controls 136 overlaid over the background video may facilitate the user adjusting the operation of the exercise device while playing the media and/or exercise program on the display (e.g., without interrupting the media and/or the exercise program).

FIG. 19 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, manual controls for the exercise device are presented overlaid over the background video. The manual controls may include incline controls 134 and speed controls 136. The incline controls 134 and the speed controls 136 may be sliders to present additional information or selectable options for the user. Presenting the incline controls 134 and the speed controls 136 overlaid over the background video may facilitate the user adjusting the operation of the exercise device while playing the media and/or exercise program on the display (e.g., without interrupting the media and/or the exercise program). In the embodiment shown, multiple widgets 118 are overlaid over the background display. Presentation of the widgets 118 has pushed the top banner 112 to the left to allow both the widget 118 and all of the elements or icons of the top banner 112 to be shown. The widgets 118 have also pushed the speed controls 136 to the left to allow both the widgets 118 and the speed controls 136 to both be accessed at the same time. The widgets 118 may include any type of information, including heartrate and/or heartrate zone information, distance, speed, calories burnt, and so forth.

FIG. 20 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, manual controls for the exercise device are presented overlaid over the background video. The manual controls may include incline controls 134 and speed controls 136. The incline controls 134 and the speed controls 136 may be sliders to present additional information or selectable options for the user. Presenting the incline controls 134 and the speed controls 136 overlaid over the background video may facilitate the user adjusting the operation of the exercise device while playing the media and/or exercise program on the display (e.g., without interrupting the media and/or the exercise

program). In the embodiment shown, multiple widgets 118 are overlaid over the background display. Presentation of the widgets 118 has pushed the top banner 112 to the left to allow both the widget 118 and all of the elements or icons of the top banner 112 to be shown. The widgets 118 have also pushed the speed controls 136 to the left to allow both the widgets 118 and the speed controls 136 to both be accessed at the same time. The widgets 118 may include any type of information, including heartrate and/or heartrate zone information, distance, speed, calories burnt, and so forth. In the embodiment shown, a chart 124 is overlaid over the background display above the lower menu 102. The chart 124 may include information associated with the exercise program, such as incline and/or speed. Multiple parameters may be illustrated on the chart 124.

FIG. 21 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a media selection menu 138 may include a plurality of selectable icons representing third-party media providers. While implementing the exercise program and/or other third-party media, the user may select one of the third-party media providers from the media selection menu 138 to identify new third-party media to watch.

FIG. 22 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a media selection menu 138 may include a plurality of selectable icons representing third-party media providers. While implementing the exercise program and/or other third-party media, the user may select one of the third-party media providers from the media selection menu 138 to identify new third-party media to watch.

FIG. 23 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a media selection menu 138 may include a plurality of selectable icons representing third-party media providers. While implementing the exercise program and/or other third-party media, the user may select one of the third-party media providers from the media selection menu 138 to identify new third-party media to watch.

FIG. 24 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a picture-in-a-picture 140 icon is displayed overlaid over the background. The picture-in-a-picture 140 may illustrate third-party media or the video portion of an exercise program.

FIG. 25 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a picture-in-a-picture 140 icon is displayed overlaid over the background.

11

The picture-in-a-picture 140 may illustrate third-party media or the video portion of an exercise program.

FIG. 26 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a picture-in-a-picture 140 icon is displayed overlaid over the background. The picture-in-a-picture 140 may illustrate third-party media or the video portion of an exercise program. In the embodiment shown, a settings menu 114 may be overlaid over the video display. The settings menu 114 may be invoked or presented based on the selection of a selectable icon. The settings menu 114 may allow the user to change one or more settings of the GUI 100, such as the presentation of one or more of settings, statistics, widgets, charts, and fullscreen mode. The settings menu 114 may move the picture-in-a-picture 140 upwards.

FIG. 27 is a representation of a GUI 100 that may be presented on a display of an exercise device, according to at least one embodiment of the present disclosure. The GUI 100 may include a background image or video display, with a lower menu 102 and a top banner 112 overlaid over the video display. In the embodiment shown, a picture-in-a-picture 140 icon is displayed overlaid over the background. The picture-in-a-picture 140 may illustrate third-party media or the video portion of an exercise program. In the embodiment shown, multiple widgets 118 are overlaid over the background display. Presentation of the widgets 118 has pushed the top banner 112 to the left to allow both the widget 118 and all of the elements or icons of the top banner 112 to be shown.

FIG. 28 is a representation of a volume control system 250, according to at least one embodiment of the present disclosure. Each of the components of the volume control system 250 can include software, hardware, or both. For example, the components can include one or more instructions stored on a computer-readable storage medium and executable by processors of one or more computing devices, such as a client device or server device. When executed by the one or more processors, the computer-executable instructions of the volume control system 250 can cause the computing device(s) to perform the methods described herein. Alternatively, the components can include hardware, such as a special-purpose processing device to perform a certain function or group of functions. Alternatively, the components of the volume control system 250 can include a combination of computer-executable instructions and hardware.

Furthermore, the components of the volume control system 250 may, for example, be implemented as one or more operating systems, as one or more stand-alone applications, as one or more modules of an application, as one or more plug-ins, as one or more library functions or functions that may be called by other applications, and/or as a cloud-computing model. Thus, the components may be implemented as a stand-alone application, such as a desktop or mobile application. Furthermore, the components may be implemented as one or more web-based applications hosted on a remote server. The components may also be implemented in a suite of mobile device applications or “apps.”

The volume control system 250 may control the volume of the sound output of an exercise program. For example, the volume control system 250 may control the volume of an exercise program package 252 and third-party media 254. The exercise program package 252 may include a control

12

stream 256, a program audio stream 258, and a program video stream 260. The control stream 256 may include exercise device controls that may cause the exercise device to adjust one or more operating parameters of the exercise device. The exercise device controls of the control stream 256 may adjust any operating parameter of the exercise device. For example, the exercise device controls of the control stream 256 may adjust operating parameters including one or more of speed, incline, resistance, and so forth.

The program audio stream 258 includes audio associated with the exercise program package 252 and the program video stream 260 includes video associated with the exercise program package 252. The program audio stream 258 and the program video stream 260 may include representations of audiovisual elements associated with performing the exercise program. For example, the program audio stream 258 may include music, sound effects, trainer dialog, any other audio associated with the exercise program package 252, and combinations thereof. The program video stream 260 may include video associated with the exercise program package 252, such as video of the trainer, an actor, a simulated environment, the user, an avatar of the user, avatars of other users, pre-recorded video of real-life locations, any other video associated with the exercise program package 252, and combinations thereof.

The control stream 256, program audio stream 258, and program video stream 260 may be synchronized. For example, changes in operating parameters represented by the exercise device controls may be synchronized or occur at the same time as audio content from the program audio stream 258 and video content from the program video stream 260. In some embodiments, elements from the control stream 256, the program audio stream 258, and the program video stream 260 may be related. For example, a trainer may discuss and/or show a user regarding a change in the operating parameters in the exercise device when the exercise device controls cause an associated change in the operating parameters of the user's exercise device.

The third-party media 254 includes a media audio stream 262 and a media video stream 264. The third-party media 254 may be any third-party media. For example, the third-party media 254 may include one or more of television shows, movies, cartoons, animations, music, any other third-party media, and combinations thereof. The third-party media 254 may be provided in any manner. For example, the third-party media 254 may be streamed from a streaming service, stored on local memory, cast from a third-party device (such as a user's mobile device), any other source, and combinations thereof. In some embodiments, the media audio stream 262 may be unrelated to the exercise program package 252. For example, the media audio stream 262 may be unrelated to the program audio stream 258 and/or the program video stream 260.

The volume control system 250 further includes a volume controller 266. The volume controller 266 may control the volume of the media audio stream 262 and the program audio stream 258. In some embodiments, the volume controller 266 may cause the audio of the media audio stream 262 and the program audio stream 258 to be played simultaneously. For example, the volume controller 266 may cause the exercise device to play both the media audio stream 262 and the program audio stream 258 while the exercise device is implementing the exercise program package 252. This may allow the user to exercise using the exercise program package 252 while watching and listening to the third-party media 254.

In accordance with at least one embodiment of the present disclosure, the volume controller 266 may adjust a relative volume between the media audio stream 262 and the program audio stream 258. The relative volume may be a representation of the total volume for the media audio stream 262 and the program audio stream 258 played by the exercise device. For example, a relative volume of 50% may indicate that the media audio stream 262 and the program audio stream 258 both represent an equal share in the total volume played out of the speakers. A relative volume of 70% for the program audio stream 258 may indicate that the program audio stream 258 may represent 70% of the total volume played out of the speakers and the media audio stream 262 may represent 30% of the total volume played out of the speakers. In some embodiments, the relative volume may be based on the maximum decibels played out of the speakers at a particular volume level. In some embodiments, the relative volume may be based on pre-determined volume levels of the program audio stream 258 and the media audio stream 262.

In some embodiments, the volume controller 266 may set the relative volume based on the pre-determined settings. For example, the exercise program package 252 may include pre-determined settings for the program audio stream 258 to prioritize the volume of the exercise program package 252 over the third-party media 254. In some examples, the third-party media 254 may include pre-determined settings for the media audio stream 262 to prioritize the volume of the third-party media 254 over the exercise program package 252. In some embodiments, the user may set the relative volume. For example, the user (using a selectable icon, such as the volume icon 132 and/or the media settings menu 116) may set the relative volume based on the user's preferences. For example, the user may prefer to prioritize the third-party media 254, allowing the user to focus on the third-party media 254 and not on the exercise program package 252. In some examples, the user may prefer to prioritize the exercise program package 252, allowing the user to focus on the exercise program package 252 and not on the third-party media 254.

In accordance with at least one embodiment of at least one embodiment of the present disclosure, the volume control system 250 may include a content manger 268. The content manger 268 may adjust the relative volume of the program audio stream 258 and the media audio stream 262 based on content of the exercise program package 252. For example, the exercise program package 252 may include content that the volume control system 250 and/or the user may desire to be prioritized. For such priority content, the content manger 268 may alter the relative volume of the program audio stream 258 and the media audio stream 262. For example, the content manger 268 may cause the program audio stream 258 to receive a higher relative volume than the media audio stream 262. This may facilitate the user receiving the priority content in the exercise program package 252.

The content manger 268 may alter the relative volume in any manner. For example, the content manger 268 may invert the relative volume (e.g., 70% media audio stream 262 and 30% program audio stream 258 inverted to 30% program audio stream 258 and 30% media audio stream 262). In some examples, the content manger 268 may increase the relative volume of the program audio stream 258 by a pre-determined amount (e.g., decrease the volume of the media audio stream 262 or increasing the relative volume of the program audio stream 258 by 10%, 20%, 30%, 40%, 50%, 60%, 70%, 80%, 90%, or any value therebetween). In some examples, the content manger 268

may increase the relative volume of the program audio stream 258 to 100% (e.g., mute the media audio stream 262). In some examples, the content manger 268 may pause the media audio stream 262.

5 In some embodiments, the content manger 268 may alter the relative volume based on user input. For example, the user may provide an input (using a selectable icon, such as the volume icon 132 and/or the media settings menu 116) to determine the amount of alteration to the relative volume by 10 the content manger 268. In some embodiments, the content manger 268 may alter the relative volume based on manufacturer specifications and/or industry regulations.

The content manger 268 may alter the relative volume based on content in the exercise program package 252. The 15 content in the exercise program package 252 may include any content. For example, the content in the exercise program package 252 may include a change in one or more exercise parameters of the exercise device. In some examples, the content in the exercise program package 252 20 may include a change in exercise type (e.g., stepping off the exercise device to perform a different exercise, transition to a second exercise device). In some examples, the content in the exercise program package 252 may include trainer dialog in the program audio stream 258. In some examples, 25 the content in the exercise program package 252 may include a particular image or video stream in the program video stream 260.

In some examples, the content of the exercise program 30 package 252 that causes the content manger 268 to alter the relative volume may include a metadata tag stored in metadata for the exercise program package 252. For example, the metadata tag may be included in a separate metadata file. In some examples, the metadata tag may be included in the control stream 256. In some examples, the metadata tag may 35 be included in the program video stream 260. In some embodiments, the metadata tag may include an instruction to the content manger 268 to alter the relative volume. The metadata tag may be synchronized to a particular time in the exercise program package 252. For example, the metadata tag 40 may be associated with a particular time of the exercise program package 252 and the content of the control stream 256, the program audio stream 258, the program video stream 260, and combinations thereof.

In some examples, the metadata tag may include an 45 urgency. The urgency may be a representation of the priority of the change in relative volume. For example, the content manger 268 may include an urgency threshold to adjust the relative volume. The urgency threshold may be based on user preferences, manufacturer standards, industry standards 50 or regulations, and so forth. If the urgency of the metadata tag exceeds the urgency threshold then the content manger 268 may alter the relative volume of the program audio stream 258 and the media audio stream 262. In some embodiments, the urgency of the metadata tag may be 55 associated with the extent of the change in the relative volume. For example, a lower urgency may be associated with a lower change in the relative volume. A higher urgency may be associated with a higher change in the relative volume. This may prioritize higher urgency content in the 60 exercise program package 252. In some embodiments, the user may change the urgency threshold and/or the change in relative volume for a particular content urgency.

FIG. 29 through FIG. 31, the corresponding text, and the 65 examples provide a number of different methods, systems, devices, and computer-readable media of the volume control system 250. In addition to the foregoing, one or more embodiments can also be described in terms of flowcharts

comprising acts for accomplishing a particular result, as shown in FIG. 29 through FIG. 31. FIG. 29 through FIG. 31 may be performed with more or fewer acts. Further, the acts may be performed in differing orders. Additionally, the acts described herein may be repeated or performed in parallel with one another or parallel with different instances of the same or similar acts.

As mentioned, FIG. 29 illustrates a flowchart of a series of acts or a method 300 for controlling an exercise device, according to at least one embodiment of the present disclosure. While FIG. 29 illustrates acts according to one embodiment, alternative embodiments may omit, add to, reorder, and/or modify any of the acts shown in FIG. 29. The acts of FIG. 29 can be performed as part of a method. Alternatively, a computer-readable medium can comprise instructions that, when executed by one or more processors, cause a computing device to perform the acts of FIG. 29. In some embodiments, a system can perform the acts of FIG. 29.

A volume control system may receive and play a program audio stream at an exercise device at 301. The program audio stream may be played with a program volume. The program volume may be the absolute volume of the program audio stream as heard by the user. The program audio stream is part of an exercise program. The exercise program includes exercise device controls that adjust an operating parameter of the exercise device. The program audio stream is synchronized with the exercise device controls.

The volume control system may receive and play a media audio stream at the exercise device at 302. The media audio stream is played with a media volume. The media volume may be the absolute volume of the media audio stream as heard by the user. Based on a content of the exercise program, the volume control system adjust a relative volume of the program audio stream to emphasize the program audio stream at 303. The relative volume may be the ratio of the program volume to the media volume, or the percentage of the program volume and the percentage of the media volume relative to the total volume played from the speakers of the exercise device. In some examples, emphasizing the program audio stream may include increasing the relative volume of the program audio stream (e.g., increasing the relative volume of the program volume). In some examples, emphasizing the program audio stream may include decreasing the relative volume of the media audio stream (e.g., decreasing the relative volume of the media volume).

As mentioned, FIG. 30 illustrates a flowchart of a series of acts or a method 400 for controlling an exercise device, according to at least one embodiment of the present disclosure. While FIG. 30 illustrates acts according to one embodiment, alternative embodiments may omit, add to, reorder, and/or modify any of the acts shown in FIG. 30. The acts of FIG. 30 can be performed as part of a method. Alternatively, a computer-readable medium can comprise instructions that, when executed by one or more processors, cause a computing device to perform the acts of FIG. 30. In some embodiments, a system can perform the acts of FIG. 30.

An exercise device may implement an exercise program on the exercise device at 401. The exercise program includes exercise device controls that adjust an operating parameter of the exercise device. The exercise program further includes a program video stream and a program audio stream. The program video stream and the program audio stream are synchronized with the exercise device controls. The program audio stream is played through speakers on the exercise device. The exercise device may present third-party media on the exercise device at 402. The exercise device may display, on a display of the exercise device, a media

video stream of the third-party media and media audio stream through the speakers of the device. When the exercise program reaches a priority content of the exercise program, a volume control system may alter a relative volume of the media audio stream at 403. In some embodiments, at the priority content, the volume control system may suppress the media video stream, such as by pausing the media video stream and/or overlaying a notice, notification, or a portion of the program video stream over the media video stream.

As mentioned, FIG. 31 illustrates a flowchart of a series of acts or a method 500 for controlling an exercise device, according to at least one embodiment of the present disclosure. While FIG. 31 illustrates acts according to one embodiment, alternative embodiments may omit, add to, reorder, and/or modify any of the acts shown in FIG. 31. The acts of FIG. 31 can be performed as part of a method. Alternatively, a computer-readable medium can comprise instructions that, when executed by one or more processors, cause a computing device to perform the acts of FIG. 31. In some embodiments, a system can perform the acts of FIG. 31.

An exercise device may implement an exercise program on the exercise device at 501. The exercise program includes a video portion and a program media stream. The video portion is displayed on a display of the exercise device and the program media stream is played on a speaker of the exercise device. While displaying the video portion on the display and playing the program media stream on the speaker of the exercise device, the exercise device receives a selection of a selectable icon overlaid over the video portion on the display at 502. Based on the selection, and while implementing the exercise program, a volume control system replaces the video portion on the display with a media video portion of a third party media and plays a media video stream simultaneously with the program media stream at 503. This may facilitate improved control over the exercise device and reduced disruptions to the exercise program when implementing the exercise program.

The selection may be any type of selection. For example, the selection may be a volume selection of a volume selectable icon. This may change a relative volume of the media video stream based on the volume selection. In some examples, the selection may be a control selectable icon overlaid over the media video stream. In some examples, the control selection may adjust at least one operating parameter of the exercise device. In some embodiments, the display includes a picture-in-a-picture icon of the video portion over the media video portion displayed on the display.

FIG. 32 illustrates certain components that may be included within a computer system 600. One or more computer systems 600 may be used to implement the various devices, components, and systems described herein.

The computer system 600 includes a processor 601. The processor 601 may be a general-purpose single or multi-chip microprocessor (e.g., an Advanced RISC (Reduced Instruction Set Computer) Machine (ARM)), a special purpose microprocessor (e.g., a digital signal processor (DSP)), a microcontroller, a programmable gate array, etc. The processor 601 may be referred to as a central processing unit (CPU). Although just a single processor 601 is shown in the computer system 600 of FIG. 6, in an alternative configuration, a combination of processors (e.g., an ARM and DSP) could be used.

The computer system 600 also includes memory 603 in electronic communication with the processor 601. The memory 603 may be any electronic component capable of storing electronic information. For example, the memory

603 may be embodied as random access memory (RAM), read-only memory (ROM), magnetic disk storage media, optical storage media, flash memory devices in RAM, on-board memory included with the processor, erasable programmable read-only memory (EPROM), electrically erasable programmable read-only memory (EEPROM) memory, registers, and so forth, including combinations thereof.

Instructions **605** and data **607** may be stored in the memory **603**. The instructions **605** may be executable by the processor **601** to implement some or all of the functionality disclosed herein. Executing the instructions **605** may involve the use of the data **607** that is stored in the memory **603**. Any of the various examples of modules and components described herein may be implemented, partially or wholly, as instructions **605** stored in memory **603** and executed by the processor **601**. Any of the various examples of data described herein may be among the data **607** that is stored in memory **603** and used during execution of the instructions **605** by the processor **601**.

A computer system **600** may also include one or more communication interfaces **609** for communicating with other electronic devices. The communication interface(s) **609** may be based on wired communication technology, wireless communication technology, or both. Some examples of communication interfaces **609** include a Universal Serial Bus (USB), an Ethernet adapter, a wireless adapter that operates in accordance with an Institute of Electrical and Electronics Engineers (IEEE) 802.11 wireless communication protocol, a Bluetooth® wireless communication adapter, and an infrared (IR) communication port.

A computer system **600** may also include one or more input devices **611** and one or more output devices **613**. Some examples of input devices **611** include a keyboard, mouse, microphone, remote control device, button, joystick, trackball, touchpad, and lightpen. Some examples of output devices **613** include a speaker and a printer. One specific type of output device that is typically included in a computer system **600** is a display device **615**. Display devices **615** used with embodiments disclosed herein may utilize any suitable image projection technology, such as liquid crystal display (LCD), light-emitting diode (LED), gas plasma, electroluminescence, or the like. A display controller **617** may also be provided, for converting data **607** stored in the memory **603** into text, graphics, and/or moving images (as appropriate) shown on the display device **615**.

The various components of the computer system **600** may be coupled together by one or more buses, which may include a power bus, a control signal bus, a status signal bus, a data bus, etc. For the sake of clarity, the various buses are illustrated in FIG. 32 as a bus system **619**.

INDUSTRIAL APPLICABILITY

This disclosure generally relates to devices, systems, and methods for controlling an exercise device. A graphical user interface for an exercise device includes one or more selectable icons presented on a video display overlaid over a video (such as third-party media and/or an exercise program). Selection of the selectable icons may facilitate changing of one or more settings of the exercise device. In accordance with at least one embodiment of the present disclosure, selection of the selectable icons may change a setting of the exercise device without interrupting playing of the media on the display. In some embodiments, selection of the selectable icons may display third-party media on the display without interrupting the implementation of the exercise

program. This may allow the user to seamlessly select and implement the exercise program and third-party media based on his or her desires and interests.

In accordance with at least one embodiment of the present disclosure, the user may adjust the relative volume of the audio streams of the exercise program and the third-party media. For example, while the user is performing a workout based on the exercise program that the exercise device implements, the user may increase the relative volume of the third-party media and decrease the relative volume of the exercise program. In some embodiments, the exercise device may, based on content of the exercise program, adjust the relative volume of the exercise program to emphasize or highlight the audio stream of the exercise program. This may facilitate the user hearing critical instructions, raising the user's awareness of changes to the operating parameters of the exercise device, and highlighting other portions of the exercise program. In this manner, the safety of the implementation of the exercise device may be increased.

Each of the components of a volume control system can include software, hardware, or both. For example, the components can include one or more instructions stored on a computer-readable storage medium and executable by processors of one or more computing devices, such as a client device or server device. When executed by the one or more processors, the computer-executable instructions of the volume control system can cause the computing device(s) to perform the methods described herein. Alternatively, the components can include hardware, such as a special-purpose processing device to perform a certain function or group of functions. Alternatively, the components of the volume control system can include a combination of computer-executable instructions and hardware.

Furthermore, the components of the volume control system may, for example, be implemented as one or more operating systems, as one or more stand-alone applications, as one or more modules of an application, as one or more plug-ins, as one or more library functions or functions that may be called by other applications, and/or as a cloud-computing model. Thus, the components may be implemented as a stand-alone application, such as a desktop or mobile application. Furthermore, the components may be implemented as one or more web-based applications hosted on a remote server. The components may also be implemented in a suite of mobile device applications or “apps.”

The volume control system may control the volume of the sound output of an exercise program. For example, the volume control system may control the volume of an exercise program and third-party media. The exercise program may include a control stream, a program audio stream, and a program video stream. The control stream may include exercise device controls that may cause the exercise device to adjust one or more operating parameters of the exercise device. The exercise device controls of the control stream may adjust any operating parameter of the exercise device. For example, the exercise device controls of the control stream may adjust operating parameters including one or more of speed, incline, resistance, and so forth.

The program audio stream includes audio associated with the exercise program and the program video stream includes video associated with the exercise program. The program audio stream and the program video stream may include representations of audiovisual elements associated with performing the exercise program. For example, the program audio stream may include music, sound effects, trainer dialog, any other audio associated with the exercise program, and combinations thereof. The program video stream

may include video associated with the exercise program, such as video of the trainer, an actor, a simulated environment, the user, an avatar of the user, avatars of other users, pre-recorded video of real-life locations, any other video associated with the exercise program, and combinations thereof.

The control stream, program audio stream, and program video stream may be synchronized. For example, changes in operating parameters represented by the exercise device controls may be synchronized or occur at the same time as audio content from the program audio stream and video content from the program video stream. In some embodiments, elements from the control stream, the program audio stream, and the program video stream may be related. For example, a trainer may discuss and/or show a user regarding a change in the operating parameters in the exercise device when the exercise device controls cause an associated change in the operating parameters of the user's exercise device.

The third-party media includes a media audio stream and a media video stream. The third-party media may be any third-party media. For example, the third-party media may include one or more of television shows, movies, cartoons, animations, music, any other third-party media, and combinations thereof. The third-party media may be provided in any manner. For example, the third-party media may be streamed from a streaming service, stored on local memory, cast from a third-party device (such as a user's mobile device), any other source, and combinations thereof. In some embodiments, the media audio stream may be unrelated to the exercise program. For example, the media audio stream may be unrelated to the program audio stream and/or the program video stream.

The volume control system further includes a volume controller. The volume controller may control the volume of the media audio stream and the program audio stream. In some embodiments, the volume controller may cause the audio of the media audio stream and the program audio stream to be played simultaneously. For example, the volume controller may cause the exercise device to play both the media audio stream and the program audio while the exercise device is implementing the exercise program. This may allow the user to exercise using the exercise program while watching and listening to the third-party media.

In accordance with at least one embodiment of the present disclosure, the volume controller may adjust a relative volume between the media audio and the program audio stream. The relative volume may be a representation of the total volume for the media audio stream and the program audio stream played by the exercise device. For example, a relative volume of 50% may indicate that the media audio stream and the program audio stream both represent an equal share in the total volume played out of the speakers. A relative volume of 70% for the program audio stream may indicate that the program audio stream may represent 70% of the total volume played out of the speakers and the media audio stream may represent 30% of the total volume played out of the speakers. In some embodiments, the relative volume may be based on the maximum decibels played out of the speakers at a particular volume level. In some embodiments, the relative volume may be based on pre-determined volume levels of the program audio stream and the media audio stream.

In some embodiments, the volume controller may set the relative volume based on the pre-determined settings. For example, the exercise program may include pre-determined settings for the program audio stream to prioritize the

volume of the exercise program over the third-party media. In some examples, the third-party media may include pre-determined settings for the media audio stream to prioritize the volume of the third-party media over the exercise program. In some embodiments, the user may set the relative volume. For example, the user (using a selectable icon, such as the volume icon and/or the media settings menu) may set the relative volume based on the user's preferences. For example, the user may prefer to prioritize the third-party media, allowing the user to focus on the third-party media and not on the exercise program. In some examples, the user may prefer to prioritize the exercise program, allowing the user to focus on the exercise program and not on the third-party media.

In accordance with at least one embodiment of at least one embodiment of the present disclosure, the volume control system may include a content manger. The content manger may adjust the relative volume of the program audio stream and the media audio stream based on content of the exercise program. For example, the exercise program may include content that the volume control system and/or the user may desire to be prioritized. For such priority content, the content manger may alter the relative volume of the program audio stream and the media audio stream. For example, the content manger may cause the program audio stream to receive a higher relative volume than the media audio stream. This may facilitate the user receiving the priority content in the exercise program.

The content manger may alter the relative volume in any manner. For example, the content manger may invert the relative volume (e.g., 70% media audio stream and 30% program audio stream inverted to 30% program audio stream and 30% media audio stream). In some examples, the content manger may increase the relative volume of the program audio stream by a pre-determined amount (e.g., decrease the volume of the media audio stream or increasing the relative volume of the program audio stream **258** by 10%, 20%, 30%, 40%, 50%, 60%, 70%, 80%, 90%, or any value therebetween). In some examples, the content manger may increase the relative volume of the program audio stream to 100% (e.g., mute the media audio stream). In some examples, the content manger may pause the media audio stream.

In some embodiments, the content manger may alter the relative volume based on user input. For example, the user may provide an input (using a selectable icon, such as the volume icon and/or the media settings menu) to determine the amount of alteration to the relative volume by the content manger. In some embodiments, the content manger may alter the relative volume based on manufacturer specifications and/or industry regulations.

The content manger may alter the relative volume based on content in the exercise program. The content in the exercise program may include any content. For example, the content in the exercise program may include a change in one or more exercise parameters of the exercise device. In some examples, the content in the exercise program may include a change in exercise type (e.g., stepping off the exercise device to perform a different exercise, transition to a second exercise device). In some examples, the content in the exercise program may include trainer dialog in the program audio stream. In some examples, the content in the exercise program may include a particular image or video stream in the program video stream.

In some examples, the content of the exercise program that causes the content manger to alter the relative volume may include a metadata tag stored in metadata for the

exercise program. For example, the metadata tag may be included in a separate metadata file. In some examples, the metadata tag may be included in the control stream. In some examples, the metadata tag may be included in the program video stream. In some embodiments, the metadata tag may include an instruction to the content manger to alter the relative volume. The metadata tag may be synchronized to a particular time in the exercise program. For example, the metadata tag may be associated with a particular time of the exercise program and the content of the control stream, the program audio stream, the program video stream, and combinations thereof.

In some examples, the metadata tag may include an urgency. The urgency may be a representation of the priority of the change in relative volume. For example, the content manger may include an urgency threshold to adjust the relative volume. The urgency threshold may be based on user preferences, manufacturer standards, industry standards or regulations, and so forth. If the urgency of the metadata tag exceeds the urgency threshold then the content manger may alter the relative volume of the program audio stream and the media audio stream. In some embodiments, the urgency of the metadata tag may be associated with the extent of the change in the relative volume. For example, a lower urgency may be associated with a lower change in the relative volume. A higher urgency may be associated with a higher change in the relative volume. This may prioritize higher urgency content in the exercise program. In some embodiments, the user may change the urgency threshold and/or the change in relative volume for a particular content urgency.

The following text, and the examples provide a number of different methods, systems, devices, and computer-readable media of the volume control system discussed herein. In addition to the foregoing, one or more embodiments can also be described in terms of flowcharts comprising acts for accomplishing a particular result, as discussed herein. The methods discussed herein may be performed with more or fewer acts. Further, the acts may be performed in differing orders. Additionally, the acts described herein may be repeated or performed in parallel with one another or parallel with different instances of the same or similar acts.

As mentioned, the methods described herein describe acts according to one embodiment, alternative embodiments may omit, add to, reorder, and/or modify any of the acts discussed herein. The acts described herein can be performed as part of a method. Alternatively, a computer-readable medium can comprise instructions that, when executed by one or more processors, cause a computing device to perform the acts described herein. In some embodiments, a system can perform the acts described herein.

A volume control system may receive and play a program audio stream at an exercise device. The program audio stream may be played with a program volume. The program volume may be the absolute volume of the program audio stream as heard by the user. The program audio stream is part of an exercise program. The exercise program includes exercise device controls that adjust an operating parameter of the exercise device. The program audio stream is synchronized with the exercise device controls.

The volume control system may receive and play a media audio stream at the exercise device. The media audio stream is played with a media volume. The media volume may be the absolute volume of the media audio stream as heard by the user. Based on a content of the exercise program, the volume control system adjust a relative volume of the program audio stream to emphasize the program audio

stream. The relative volume may be the ratio of the program volume to the media volume, or the percentage of the program volume and the percentage of the media volume relative to the total volume played from the speakers of the exercise device. In some examples, emphasizing the program audio stream may include increasing the relative volume of the program audio stream (e.g., increasing the relative volume of the program volume). In some examples, emphasizing the program audio stream may include decreasing the relative volume of the media audio stream (e.g., decreasing the relative volume of the media volume).

An exercise device may implement an exercise program on the exercise device. The exercise program includes exercise device controls that adjust an operating parameter of the exercise device. The exercise program further includes a program video stream and a program audio stream. The program video stream and the program audio stream are synchronized with the exercise device controls. The program audio stream is played through speakers on the exercise device. The exercise device may present third-party media on the exercise device. The exercise device may display, on a display of the exercise device, a media video stream of the third-party media and media audio stream through the speakers of the device. When the exercise program reaches a priority content of the exercise program, a volume control system may alter a relative volume of the media audio stream. In some embodiments, at the priority content, the volume control system may suppress the media video stream, such as by pausing the media video stream and/or overlaying a notice, notification, or a portion of the program video stream over the media video stream.

An exercise device may implement an exercise program on the exercise device. The exercise program includes a video portion and a program media stream. The video portion is displayed on a display of the exercise device and the program media stream is played on a speaker of the exercise device. While displaying the video portion on the display and playing the program media stream on the speaker of the exercise device, the exercise device receives a selection of a selectable icon overlaid over the video portion on the display. Based on the selection, and while implementing the exercise program, a volume control system replaces the video portion on the display with a media video portion of a third party media and plays a media video stream simultaneously with the program media stream. This may facilitate improved control over the exercise device and reduced disruptions to the exercise program when implementing the exercise program.

The selection may be any type of selection. For example, the selection may be a volume selection of a volume selectable icon. This may change a relative volume of the media video stream based on the volume selection. In some examples, the selection may be a control selectable icon overlaid over the media video stream. In some examples, the control selection may adjust at least one operating parameter of the exercise device. In some embodiments, the display includes a picture-in-a-picture icon of the video portion over the media video portion displayed on the display.

One or more computer systems may be used to implement the various devices, components, and systems described herein. The computer system includes a processor. The processor may be a general-purpose single or multi-chip microprocessor (e.g., an Advanced RISC (Reduced Instruction Set Computer) Machine (ARM)), a special purpose microprocessor (e.g., a digital signal processor (DSP)), a microcontroller, a programmable gate array, etc. The processor may be referred to as a central processing unit (CPU).

Although just a single processor is discussed herein, in an alternative configuration, a combination of processors (e.g., an ARM and DSP) could be used.

The computer system also includes memory in electronic communication with the processor. The memory may be any electronic component capable of storing electronic information. For example, the memory may be embodied as random access memory (RAM), read-only memory (ROM), magnetic disk storage media, optical storage media, flash memory devices in RAM, on-board memory included with the processor, erasable programmable read-only memory (EPROM), electrically erasable programmable read-only memory (EEPROM) memory, registers, and so forth, including combinations thereof.

Instructions and data may be stored in the memory. The instructions may be executable by the processor to implement some or all of the functionality disclosed herein. Executing the instructions may involve the use of the data that is stored in the memory. Any of the various examples of modules and components described herein may be implemented, partially or wholly, as instructions stored in memory and executed by the processor. Any of the various examples of data described herein may be among the data that is stored in memory and used during execution of the instructions by the processor.

A computer system may also include one or more communication interfaces for communicating with other electronic devices. The communication interface(s) may be based on wired communication technology, wireless communication technology, or both. Some examples of communication interfaces include a Universal Serial Bus (USB), an Ethernet adapter, a wireless adapter that operates in accordance with an Institute of Electrical and Electronics Engineers (IEEE) 802.11 wireless communication protocol, a Bluetooth® wireless communication adapter, and an infrared (IR) communication port.

A computer system may also include one or more input devices and one or more output devices. Some examples of input devices include a keyboard, mouse, microphone, remote control device, button, joystick, trackball, touchpad, and lightpen. Some examples of output devices include a speaker and a printer. One specific type of output device that is typically included in a computer system is a display device. Display devices used with embodiments disclosed herein may utilize any suitable image projection technology, such as liquid crystal display (LCD), light-emitting diode (LED), gas plasma, electroluminescence, or the like. A display controller may also be provided, for converting data stored in the memory into text, graphics, and/or moving images (as appropriate) shown on the display device.

The various components of the computer system may be coupled together by one or more buses, which may include a power bus, a control signal bus, a status signal bus, a data bus, etc. For the sake of clarity, the various buses are discussed herein as a bus system.

Following are sections in accordance with at least one embodiment of the present disclosure:

A1. A method implemented on an exercise device, the method comprising:
receiving and playing a program audio stream at the exercise device, the program audio stream played with a program volume, wherein the program audio stream is part of an exercise program, the exercise program including exercise device controls that adjust an operating parameter of the exercise device, the program audio stream synchronized with the exercise device controls;

receiving and playing a media audio stream at the exercise device, the media audio stream played with a media volume; and

based on a content of the exercise program, adjusting a relative volume of the program audio stream to emphasize the program audio stream.

A2. The method of section A1, wherein the media audio stream is unrelated to the exercise program.

A3. The method of any of sections A1 or A2, wherein adjusting the relative volume of the program audio stream includes decreasing a volume of the media audio stream.

A4. The method of section A3, wherein decreasing the volume of the media audio stream includes muting the media audio stream.

A5. The method of section A4, wherein muting the media audio stream includes pausing the media audio stream.

A6. The method of any of sections A1-A5, further comprising, based on a content of the media audio stream, adjusting a relative volume of the media audio stream.

A7. The method of any of sections A1-A6, wherein the content of the exercise program includes a change in one or more exercise parameters.

A8. The method of any of sections A1-A7, wherein the content of the exercise program includes a change in an exercise type.

A9. The method of any of sections A1-A8, wherein the content of the exercise program includes a metadata tag stored in metadata for the program audio stream.

A10. The method of section A9, wherein the metadata tag includes an urgency, and wherein, adjusting the relative volume includes adjusting the relative volume when the urgency is above an urgency threshold.

A11. The method of any of sections A1-A10, wherein the content of the exercise program includes dialog by a trainer.

A12. The method of any of sections A1-A11, wherein the content of the exercise program includes an image or video portion in a video portion of the exercise program.

B1. A method implemented on an exercise device, the method comprising:
implementing an exercise program, the exercise program including exercise device controls that adjust an operating parameter of the exercise device, a program video stream, and a program audio stream, the program video stream and the program audio stream synchronized with the exercise device controls, the program audio stream played through speakers on the exercise device;

presenting third-party media on the exercise device, including displaying, on a display of the exercise device, a media video stream of the third-party media and a media audio stream through the speakers; and

when the exercise program reaches a priority content, altering a relative volume of the media audio stream.

B2. The method of section B1, wherein the priority content is based on a change in the exercise device controls.

B3. The method of any of sections B1 or B2, wherein the priority content is based on an urgency in metadata for the exercise program.

B4. The method of any of sections B1-B3, wherein altering the relative volume includes reducing a media volume of the media audio stream and increasing a program volume of the program audio stream.

B5. The method of any of sections B1-B4, further comprising, at the priority content, suppressing the media video stream.

B6. The method of any of sections B1-B5, wherein suppressing the media video stream includes pausing the media video stream and the media audio stream.

C1. A method for operating an exercise device, the method comprising:

implementing an exercise program on the exercise device, the exercise program including a video portion and a program media stream, the video portion displayed on a display of the exercise device and the program media stream played on a speaker of the exercise device;

while displaying the video portion on the display and playing the program media stream on the speaker of the exercise device, receiving a selection of a selectable icon overlaid over the video portion on the display; and

based on the selection, and while implementing the exercise program, replacing the video portion on the display with a media video portion of a third party media and playing a media video stream simultaneously with the program media stream.

C2. The method of section C1, further comprising receiving a volume selection of a volume selectable icon and changing a relative volume of the media video stream based on the volume selection.

C3. The method of any of sections C1 or C2, further comprising presenting a control selectable icon overlaid over the media video stream.

C4. The method of section C3, further comprising: receiving a control selection of the control selectable icon; and

based on the control selection, adjusting at least one operating parameter of the exercise device.

C5. The method of any of sections C1-C4, further comprising presenting a picture-in-a-picture icon of the video portion over the media video portion displayed on the display.

Embodiments of the present disclosure may thus utilize a special purpose or general-purpose computing system including computer hardware, such as, for example, one or more processors and system memory. Embodiments within the scope of the present disclosure also include physical and other computer-readable media for carrying or storing computer-executable instructions and/or data structures, including applications, tables, data, libraries, or other modules used to execute particular functions or direct selection or execution of other modules. Such computer-readable media can be any available media that can be accessed by a general purpose or special purpose computer system. Computer-readable media that store computer-executable instructions (or software instructions) are physical storage media. Computer-readable media that carry computer-executable instructions are transmission media. Thus, by way of example, and not limitation, embodiments of the present disclosure can include at least two distinctly different kinds of computer-readable media, namely physical storage media or transmission media. Combinations of physical storage media and transmission media should also be included within the scope of computer-readable media.

Both physical storage media and transmission media may be used temporarily store or carry, software instructions in the form of computer readable program code that allows performance of embodiments of the present disclosure. Physical storage media may further be used to persistently or

permanently store such software instructions. Examples of physical storage media include physical memory (e.g., RAM, ROM, EPROM, EEPROM, etc.), optical disk storage (e.g., CD, DVD, HDDVD, Blu-ray, etc.), storage devices (e.g., magnetic disk storage, tape storage, diskette, etc.), flash or other solid-state storage or memory, or any other non-transmission medium which can be used to store program code in the form of computer-executable instructions or data structures and which can be accessed by a general purpose or special purpose computer, whether such program code is stored as or in software, hardware, firmware, or combinations thereof.

A “network” or “communications network” may generally be defined as one or more data links that enable the transport of electronic data between computer systems and/or modules, engines, and/or other electronic devices. When information is transferred or provided over a communication network or another communications connection (either hardwired, wireless, or a combination of hardwired or wireless) to a computing device, the computing device properly views the connection as a transmission medium. Transmission media can include a communication network and/or data links, carrier waves, wireless signals, and the like, which can be used to carry desired program or template code means or instructions in the form of computer-executable instructions or data structures and which can be accessed by a general purpose or special purpose computer.

Further, upon reaching various computer system components, program code in the form of computer-executable instructions or data structures can be transferred automatically or manually from transmission media to physical storage media (or vice versa). For example, computer-executable instructions or data structures received over a network or data link can be buffered in memory (e.g., RAM) within a network interface module (NIC), and then eventually transferred to computer system RAM and/or to less volatile physical storage media at a computer system. Thus, it should be understood that physical storage media can be included in computer system components that also (or even primarily) utilize transmission media.

One or more specific embodiments of the present disclosure are described herein. These described embodiments are examples of the presently disclosed techniques. Additionally, in an effort to provide a concise description of these embodiments, not all features of an actual embodiment may be described in the specification. It should be appreciated that in the development of any such actual implementation, as in any engineering or design project, numerous embodiment-specific decisions will be made to achieve the developers' specific goals, such as compliance with system-related and business-related constraints, which may vary from one embodiment to another. Moreover, it should be appreciated that such a development effort might be complex and time consuming, but would nevertheless be a routine undertaking of design, fabrication, and manufacture for those of ordinary skill having the benefit of this disclosure.

The articles “a,” “an,” and “the” are intended to mean that there are one or more of the elements in the preceding descriptions. The terms “comprising,” “including,” and “having” are intended to be inclusive and mean that there may be additional elements other than the listed elements. Additionally, it should be understood that references to “one embodiment” or “an embodiment” of the present disclosure are not intended to be interpreted as excluding the existence of additional embodiments that also incorporate the recited features. For example, any element described in relation to

an embodiment herein may be combinable with any element of any other embodiment described herein. Numbers, percentages, ratios, or other values stated herein are intended to include that value, and also other values that are “about” or “approximately” the stated value, as would be appreciated by one of ordinary skill in the art encompassed by embodiments of the present disclosure. A stated value should therefore be interpreted broadly enough to encompass values that are at least close enough to the stated value to perform a desired function or achieve a desired result. The stated values include at least the variation to be expected in a suitable manufacturing or production process, and may include values that are within 5%, within 1%, within 0.1%, or within 0.01% of a stated value.

A person having ordinary skill in the art should realize in view of the present disclosure that equivalent constructions do not depart from the spirit and scope of the present disclosure, and that various changes, substitutions, and alterations may be made to embodiments disclosed herein without departing from the spirit and scope of the present disclosure. Equivalent constructions, including functional “means-plus-function” clauses are intended to cover the structures described herein as performing the recited function, including both structural equivalents that operate in the same manner, and equivalent structures that provide the same function. It is the express intention of the applicant not to invoke means-plus-function or other functional claiming for any claim except for those in which the words ‘means for’ appear together with an associated function. Each addition, deletion, and modification to the embodiments that falls within the meaning and scope of the claims is to be embraced by the claims.

The terms “approximately,” “about,” and “substantially” as used herein represent an amount close to the stated amount that still performs a desired function or achieves a desired result. For example, the terms “approximately,” “about,” and “substantially” may refer to an amount that is within less than 5% of, within less than 1% of, within less than 0.1% of, and within less than 0.01% of a stated amount. Further, it should be understood that any directions or reference frames in the preceding description are merely relative directions or movements. For example, any references to “up” and “down” or “above” or “below” are merely descriptive of the relative position or movement of the related elements.

The present disclosure may be embodied in other specific forms without departing from its spirit or characteristics. The described embodiments are to be considered as illustrative and not restrictive. The scope of the disclosure is, therefore, indicated by the appended claims rather than by the foregoing description. Changes that come within the meaning and range of equivalency of the claims are to be embraced within their scope.

What is claimed is:

1. A method implemented on an exercise device, the method comprising:

playing, at the exercise device, a program audio stream of an exercise program package, the program audio stream played with a program volume, the exercise program package including exercise device controls that adjust an operating parameter of the exercise device, and wherein the program audio stream is synchronized with the exercise device controls; receiving and playing a media audio stream at the exercise device, the media audio stream played with a media volume; and

based on a content of the exercise program package, adjusting a relative volume of the program audio relative to the media volume to emphasize the program audio stream.

5 2. The method of claim 1, wherein the media audio stream is unrelated to the exercise program package.

3. The method of claim 1, wherein adjusting the relative volume of the program audio stream includes decreasing a volume of the media audio stream.

10 4. The method of claim 3, wherein decreasing the volume of the media audio stream includes muting the media audio stream.

5. The method of claim 4, wherein muting the media audio stream includes pausing the media audio stream.

6. The method of claim 1, further comprising, based on a content of the media audio stream, adjusting a relative volume of the media audio stream.

7. The method of claim 1, wherein the content of the 20 exercise program package includes a change in one or more exercise parameters.

8. The method of claim 1, wherein the content of the exercise program package includes a change in an exercise type.

25 9. The method of claim 1, wherein the content of the exercise program package includes a metadata tag stored in metadata for the program audio stream.

10. The method of claim 9, wherein the metadata tag includes an urgency, and wherein, adjusting the relative volume includes adjusting the relative volume when the urgency is above an urgency threshold.

11. The method of claim 1, wherein the content of the exercise program package includes dialog by a trainer.

12. The method of claim 1, wherein the content of the 35 exercise program package includes an image or video portion in a video portion of the exercise program package.

13. A method implemented on an exercise device, the method comprising:

implementing an exercise program package, the exercise program package including exercise device controls that adjust an operating parameter of the exercise device, a program video stream, and a program audio stream, the program video stream and the program audio stream synchronized with the exercise device controls, the program audio stream played through speakers on the exercise device;

presenting third-party media on the exercise device, including displaying, on a display of the exercise device, a media video stream of the third-party media and a media audio stream through the speakers; and when the exercise program package reaches a priority content, altering a relative volume of the media audio stream.

14. The method of claim 13, wherein the priority content 55 is based on a change in the exercise device controls.

15. The method of claim 13, wherein the priority content is based on an urgency in metadata for the exercise program package.

16. The method of claim 13, wherein altering the relative 60 volume includes reducing a media volume of the media audio stream and increasing a program volume of the program audio stream.

17. The method of claim 13, further comprising, at the priority content, suppressing the media video stream.

18. The method of claim 17, wherein suppressing the media video stream includes pausing the media video stream and the media audio stream.

19. A method for operating an exercise device, the method comprising:

implementing an exercise program package on the exercise device, the exercise program package including a video portion and a program media stream, the video portion displayed on a display of the exercise device and the program media stream played on a speaker of the exercise device;

while displaying the video portion on the display and playing the program media stream on the speaker of the exercise device, receiving a selection of a selectable icon overlaid over the video portion on the display; and based on the selection, and while implementing the exercise program package, replacing the video portion on the display with a media video portion of a third party media and playing a media video stream simultaneously with the program media stream.

20. The method of claim 19, further comprising receiving a volume selection of a volume selectable icon and changing a relative volume of the media video stream based on the volume selection.
